ELEVATED WATER TANK

James O. Jackson, Crafton, Pa.

Application October 27, 1933, Serial No. 695,467

5 Claims. (Cl. 220—69)

My invention relates to elevated water tanks supported by steel towers.

Such tanks as heretofore constructed have been provided either with a flat base extending to the vertical side of the tank, the base being supported by pillars throughout the area of the flat bottom or a hemispherical bottom has been employed supported by pillars located at the periphery of the bottom. The latter type of tank while offering many advantages over the flat bottom tank has the distinct disadvantage that the variation in the head of water contained in it between the full and empty water levels is so great as to render this type of tank objectionable in many installations. This unsatisfactory condition created a demand for elevated tanks with smaller ranges of head than were possible with hemispherical bottoms and the bottoms were therefore made hemiellipsoidal in shape in which the range of head as compared to the tank diameter was considerably reduced. As the demand grew for tanks of still larger capacity, it became increasingly difficult to use the hemiellipsoidal form of bottom because of the large tensional stresses in the central portions of such bottoms arising from their relative flatness. At the same time the further refinements of municipal water works systems required tanks of still smaller ranges of head in order to permit more uniform pumping operations.

It is the purpose of my invention to produce an elevated water tank having advantages not possessed by prior tanks while eliminating many of their disadvantages. My new type of tank is provided with a bottom having its central portion substantially flat while a substantial part of the bottom between the flat portion and the side of the tank is inclined downwardly and inwardly substantially tangent to the bottom. Supporting pillars are provided under the side of the tank and under the flat bottom only, no pillars being employed under the toroidal portion of the bottom.

When the tank is filled with water a column of the water having the same diameter as the flat portion of the bottom and extending to the surface of the water in the tank is supported by the pillars under the flat portion of the bottom.

The weight of the water above the toroidal portion of the bottom is supported by the pillars around the shell of the tank and additional pillars or other supporting structure under the toroidal portion of the bottom become entirely unnecessary and can be dispensed with at a great sav-

ing of cost and an improvement in the appearance of the tank.

By utilizing my toroidal construction of tank it is possible, for instance, to eliminate over one half of the grillage and girder beams required for a flat bottom tank at the sacrifice of only about seven percent of the total volume of the tank while maintaining the advantages of small variation in head of the water and this small reduction in capacity can be neutralized by a trivial increase in diameter of the tank.

Referring to the accompanying drawing, Fig. 1 is a side elevation of an elevated water tank constructed in accordance with this invention, the supporting columns and the riser pipe being broken away shortly below their upper ends. Fig. 2 is an enlarged cross-section of Fig. 1, the section extending from one side of the structure to some distance beyond the vertical center of the tank. Fig. 3 is an enlarged section on the line 3—3 on Fig. 1. Figs. 4 and 5 are vertical sections on the lines 4—4 and 5—5 respectively on Fig. 3.

On the drawing, 10 designates a tank shell having the upper cylindrical portion 11 and the lower toroidal portion 12 which has its upper edge welded to the lower edge of the cylindrical portion 11. The lower end of the curved lateral wall of the toroidal portion 12 is closed by the bottom 13 which is substantially flat or slightly convergent toward its center.

The tank shell is supported by a steel tower having the outer ring of columns 14 which have their upper ends secured to the cylindrical portion 11 of the tank and the upper portion of the toroidal portion 12 by welding or other securing means. Within the ring of columns 14 are two rings of columns 15 concentric with the outer ring of columns. The columns of the two inner rings are arranged in pairs, each pair being radially positioned in vertical planes conceived as projecting from the axial center of the tank. The columns 15 support a grillage composed of radial girders 16, each supported on a radial pair of columns 15, and the grillage beams 17 having their ends supported by the radial girders 16. The outer ends of the radial girders have welded to them a circular girder 18 and the inner ends of these girders have the circular girders 19 welded to them. The girders 16 and the beams 17 are preferably I-beams, but they may have other shapes if desired. The ends of the beams 17 are fitted beneath the upper flanges of the girders 16 and are connected to the webs of the girders 16 by the angles 20 riveted both to the

beams and the girders 16, but the girders 16 and the beams 17 may be secured together by other means, such as welding. It will be noted that the beams 17 are arranged in the perimeters of a series of polygons, one within another, the upper faces of the girders 16 and the beams 17 all lying at about the same level or slightly inclined toward the center of the bottom.

The lower edge of the curved portion of the toroid 12 is welded to the upper face of the circular girder 18. The bottom of the toroid is made up of a series of steel plates 21, each plate spanning the space between the consecutive radial girders 16, the ends of the plates being welded to the upper surface of the radial girders. The plates 21 between each two consecutive radial girders are arranged edge to edge to form a continuous surface. The lateral edges of the plates rest upon the beams and are welded together so as to form seams of polygonal shape overlying the longitudinal centers of the polygonal series of beams. The lower faces of the plates are welded to the beams as well as to the radial and circular girders. The bottom within the outermost girders 17 is formed of nearly triangular areas converging toward the center of the bottom. The end edges are welded along seams 23 overlying the longitudinal center of the radial girders. All of the welds in the bottom are supported by the girders and beams which are arranged on the lines of the natural expansion of the tank so that there is practically no liability of strains which will cause leaking along the seams, if the welds have been correctly made.

Plates 21' are welded to the outermost plate 21 of each section and to the outer circular girder 18.

24 designates a vertical riser pipe having its upper end coincident with the opening 25 in the bottom of the tank. The upper end of the riser pipe is secured to the bottom of the tank in any satisfactory manner as by welding or riveting. The riser pipe and the columns 14 and 15 are supported on suitable foundations, not shown.

26 is a roof for the tank which may be omitted if desired.

The two columns 15 which support a radial girder 16 are so positioned that the bending moments at the three points of contra-flexure are substantially equal.

50 The inner ends of the radial girders and the circular girder 19 are spaced a substantial distance from the riser pipe 24 so as to allow the annulus of the bottom between the riser pipe and the circular girder 19 to have sufficient vertical 55 deflection due to the expansion and contraction of the riser pipe.

I claim:

1. An elevated tank structure comprising a circular flat bottom portion bounded by a toroidal

wall portion rising from its periphery extending outwardly and upwardly therefrom, said flat portion and said toroidal portion dividing the supporting bottom area into two substantial supporting areas, said flat bottom portion comprising sheet metal, girder reinforced throughout its area, and having posts thereunder to sustain the weight on the flat bottom, a containing shell circular in horizontal cross section connected to the outer periphery of the toroidal portion, and circumferentially spaced posts attached to the shell and having sufficient strength and proportions to sustain the weight of liquid vertically above the said toroidal portion.

2. An elevated tank structure comprising a circular flat bottom portion bounded by a toroidal wall portion rising from the periphery of said flat bottom portion and extending outwardly and upwardly therefrom, said flat bottom portion and said toroidal portion dividing the supporting bottom area into two substantial supporting areas, said flat bottom portion comprising a sheet metal floor, means reinforcing said floor and maintaining it in substantially flat condition against warping, and means under the flat bottom portion of sufficient strength to sustain the weight of liquid vertically above the said flat bottom portion, a containing shell circular in horizontal cross section connected to the outer periphery of the toroidal portion and circumferentially spaced posts attached to the shell and having sufficient strength and proportions to sustain the weight of liquid vertically above the said toroidal portion.

3. An elevated tank structure comprising a circular flat bottom portion bounded by a toroidal wall portion rising from the periphery of said flat bottom portion and extending outwardly and upwardly therefrom, said flat bottom portion and said toroidal portion dividing the supporting bottom area into two substantial supporting areas, said flat bottom portion comprising a sheet metal floor, means reinforcing said floor and maintaining it in substantially flat condition against warping, and means under the flat bottom portion of sufficient strength to sustain the weight of liquid vertically above the said flat bottom portion, and circumferentially spaced posts attached to the upper periphery of said toroidal portion and having sufficient strength and proportion to sustain the weight of liquid vertically above the said toroidal portion.

4. The combination as defined in claim 3 in which a sheet metal riser is flexibly attached to said flat bottom portion.

5. The combination as defined in claim 2 in which the said containing shell is cylindrical in shape.

JAMES O. JACKSON.
